UNITED STATES PATENT OFFICE.

ENOGAT C. PRADIER, OF DETROIT, MICHIGAN, ASSIGNOR TO SOCIÉTÉ ANONYME DU CARBURATEUR ZENITH, OF LYON, FRANCE, A CORPORATION OF FRANCE.

CARBURETER.

1,251,570.

Specification of Letters Patent.

Patented Jan. 1, 1918.

Application filed November 3, 1914. Serial No. 870,053.

To all whom it may concern:

Be it known that I, ENOGAT C. PRADIER, a citizen of the French Republic, residing at Detroit, in the county of Wayne and State 5 of Michigan, have invented a new and useful Carbureter, of which the following is a full, clear, and exact description, reference being had to the accompanying drawings, forming part of this specification, in which—

10 Figure 1 is a vertical longitudinal section showing one form of my improved carbureter.

Fig. 2 is a cross section on the line II—II of Fig. 1, and

15 Fig. 3 is a partial longitudinal section showing another form of the invention.

20 My invention relates to that type of carbureter wherein there are two separate streams of gasolene, either split from a common flow channel or consisting of two separate supply channels. In the well known zenith type of carbureter, described in the United States patent to Baverley, No. 907, 25 953, dated December 29, 1908, these separate gasolene streams are fed to two separate nozzles or jets. One of these flows is fed into an atmospheric well where the suction is practically killed, so that the suction flow to the other nozzle is compensated 30 as it grows richer under higher suction, by the flow through the well controlled jet, which is either practically constant or increases at less than the normal rate.

35 My invention is related to this general type of carbureter and is designed to provide a cheaper and simpler form wherein the two streams after passing control points are joined before they reach the jet or nozzle opening. In other words, whereas heretofore the two streams were only joined in the carbureter chamber after emerging from the jets to the jet openings, I join them before they reach the jet opening.

40 In this way a single jet opening is sufficient, and a simpler construction is afforded which also provides for supplying air through the center of the nozzle, if desired.

45 In the drawings, referring to Figs. 1 and 2, 2 represents the usual constant level 50 chamber, the level in which is shown as con-

trolled by the ordinary float 3 and valve 4. 5 is the inlet nozzle, and 6 the air vent above the gasolene therein.

From this constant level the gasolene flows through a passage or channel 7 into a cavity 8 where it is branched or split. One portion passes up through a micrometer hole in a nut 9 into a well 10 having in its upper portion air vent openings 11 leading to the atmosphere. There may be one 55 or more of these openings of any desirable size. The gasolene passes from the well to a common chamber 14, while the other portion of gasolene from the cavity 8 leads through a micrometer hole in nut 12 to a 60 cavity 13, which also communicates with the jet chamber 14.

65 In the form shown, an air tube 15 extends up through this cavity to the top of the nozzle or jet tube 16, thus giving an annular 70 or ring shaped nozzle, in which the two branch flows are joined and from which they are drawn out by the suction in the engine intake 17.

75 In the specific form shown the nuts 9 and 12 having the micrometer holes are accessible for removal and replacing of the nuts through openings controlled by nuts 18 and 19; and the air tube 15 is secured to a removable nut 20 screwed in the bottom of 80 the casting.

85 The gasolene flows from the well 10 to the common chamber 14 through a constricted opening 21, this being preferably made accessible through an opening in the outer 85 wall of the structure, which is closed by a nut 22.

90 The air entering at 23 is sucked up over the nozzle and joins with the gasolene from the two flows fed to said annular nozzle. The ordinary Venturi tube is shown at 24 and the usual butterfly throttle valve at 25.

95 To provide for easy starting, I preferably provide a depending feed tube 26 which hangs down in the well 10 with its open lower end slightly above the bottom of the well, the upper portion of this tube being secured to a bushing 27 resting on shoulders of the lower casting, the castings being preferably joined on the line $a-b$, as shown 100.

in Fig. 1. This bushing has a small hole 28 leading to a cavity 29 opening to the atmosphere through a hole 30 controlled by a conical thumb screw 31, by which the amount 5 of sub-atmosphere in the starting tube may be regulated. From the cavity 29 a feed channel 32 leads into the intake passage opposite the throttle 25 when closed.

In the operation of the device, the main 10 gasolene flow through the channel 7, which is of more than ample capacity to supply the total suction as fixed by the ring jet is split at the two flows, one passing up into the well through the regulated control orifice 9, 15 and thence through control orifice 21 to the jet, while the other flow passes through the control opening in nut 12 into the same annular jet cavity. At rest, the gasolene will stand at the same level in the constant level 20 chamber, the atmospheric well, the starting tube, and the annular jet. When the throttle is slightly opened and the engine turned over, the gasolene will be sucked out of the feed tube 26, giving a richer mixture for 25 starting, and as the throttle is further opened the two compensating jets will then feed the engine, the main jet supplies a mixture which would grow richer as the speed increases, while the well controlled branch 30 gives a supply which is either constant or grows richer at less than the normal rate, the two feeds thus combining to give a mixture which is practically constant at all speeds.

35 In Fig. 3 I show a form similar to that of Figs. 1 and 2, except that the jet is a plain, ordinary jet with no central air tube supplying air to the center of the jet opening. In this form, similar parts are marked with 40 similar numerals, with the prime mark applied thereto. In this case the common chamber 14' which is in communication with the bottom of the jet tube 16' receives the gasolene through a constricted opening 21' 45 from the well 10' and through an opening in a nut 12'. In this case the bottom nut 20' is solid and the nut 12' is adapted to be removed through the screw threaded opening in which the nut 20' is seated.

50 Another feature of my invention, not claimed herein, lies in the means for attaching the float to its stem which forms the control valve for the entry of gasolene to the float chamber. The float 3 is ordinarily soldered to its needle valve stem. As these 55 floats necessarily vary slightly in weight and size, it is important to obtain an adjustment of the float relative to its stem in order to bring the level to the proper point. 60 To obtain this in a cheaper and better way without soldering, I provide the stem with two pins 33 and 34, a spring 35 being placed between the lower pin 34 and the recessed lower portion of the float. Washers 36 are

provided between the top of the float and the 65 pin 33; and by changing these washers the positioning of the float on the stem may be easily adjusted, as desired. The washers may be used either at the top or bottom, or both, of the float, and the spring will keep 70 the float in its adjusted position, depending on the positioning and number of the washers. The float may, of course, be made of cork or other light material instead of a hollow metallic vessel. In this case, again, 75 the float would require adjustment the same as in a hollow float. The adjustment will also serve to compensate for any inaccurate machining or adjustment of the parts.

The advantages of my invention result 80 from the simplicity and cheapness of the device and the substantially constant mixture which is obtained at varying suctions and loads. The controlled constrictions are between the point of branching or splitting the 85 flow and the point where the flows again unite before being drawn out of the jet. A single jet may thus be employed, while giving the same advantages as in the usual zenith type. It will be noticed that the Venturi tube is clamped in place by the mere act of joining the upper and lower castings on the line *a*—*b*, which also clamps the bushing which carries the starting tube. The device is of relatively few parts and may be 90 cheaply and easily made and assembled. The nuts 9 and 12 are alike and are of small size, thus being easily and cheaply made. These nuts are all preferably packed, as 95 shown.

100 Many variations may be made in the form and arrangement of the parts without departing from my invention.

I claim:

1. A carbureter having a constant level 105 chamber and an atmospheric well open to the air, a common chamber supplying the jet opening, two channels having controlling openings leading from the constant level chamber, one leading to the well and the other to the common chamber, and a channel having a control opening and leading from the well to the common chamber; substantially as described.

2. A carbureter having a constant level 115 chamber, a well outside of said chamber and open to the atmosphere, a common chamber supplying the jet opening, two channels having controlling openings leading from the constant level chamber, one leading to the well and the other to the common chamber, and a channel having a control opening and leading from the well to the common chamber; substantially as described.

3. A carbureter having an annular jet 125 opening surrounding an air supply, said jet opening being arranged to feed gasolene upwardly therethrough into common chamber at

the bottom of said jet opening, and a plurality of gasoline supply channels each having an independent control communicating with said common chamber and arranged to continuously feed fuel thereto; substantially as described.

4. A carbureter having a constant level chamber, a well outside of the chamber and open to the air, a common chamber feeding the jet opening, feed channels having control openings leading from the constant level chamber to the well and the common chamber respectively, and a channel leading from the well to the common chamber; substantially as described.

5. A carbureter having a constant level chamber, a well outside of the chamber and open to the air, a common chamber feeding the jet opening, feed channels having control openings leading from the constant level chamber to the well and the common chamber respectively, and a channel leading from the well to the common chamber, the control openings being formed in removable bushings having calibrated perforations; substantially as described.

6. In a carbureter, a constant level supply chamber, a common chamber below the level of the fuel, in the constant level supply chamber, a single annular jet opening leading from the common chamber around an air tube, and two gasoline supplies leading from the constant level supply chamber to said common chamber, each supply having an independent feed control device; substantially as described.

7. A carbureter having a casing and a cover, there being a horizontal joint between the casing and the cover, said casing having a float chamber, an atmospheric well and an engine intake passage extending therethrough, the cover having an engine intake extending therethrough and in line with the engine intake through the casing, said cover extending over the atmospheric well and the float chamber and forming closures therefor, and means for securing the cover to the casing; substantially as described.

8. A carbureter having a constant level chamber, a well outside of the chamber and open to the air, a common chamber feeding the jet opening, feed channels having control openings leading from the constant level chamber to the well and the common chamber respectively, a channel leading from the well to the common chamber, said channels being arranged to give a continuous feed during operation, the control openings being formed in removable bushings having calibrated perforations and seated in the inner walls of the channels, and removable plugs giving access to said bushings in the outer walls of said channels; substantially as described.

9. A carbureter having a constant level supply chamber, a jet opening communicating with the engine intake, an atmospheric well communicating with the supply chamber, a connection leading from the atmospheric well to the engine intake, a common chamber communicating with the jet below the constant level of the supply chamber, a supply channel connected to said chamber and the supply chamber, and a second supply channel connected to the common chamber and the atmospheric well; substantially as described.

10. A carbureter comprising a float chamber, an oil feed leading thereto, a float in said chamber for maintaining a constant level therein, a vertical jet tube, an atmospheric well between the jet tube and the float chamber, a common chamber below the constant level of the oil in the float chamber and communicating with the jet feed, an oil supply channel communicating with said common chamber and the atmospheric well, and an oil supply channel communicating with the common chamber and the float chamber, said channels being arranged to constantly feed fuel during operation; substantially as described.

11. A carbureter having a constant level chamber and an atmospheric well open to the air, a common chamber supplying the jet opening, two channels having controlling openings leading from the constant level chamber, one leading to the well and the other to the common chamber, and a channel having a control opening leading from the well to the common chamber, the well having a supply channel leading to the carbureting chamber at a point above the jet; substantially as described.

12. A carbureter having a constant level chamber and an atmospheric well open to the air, a common chamber supplying the jet opening, two channels having controlling openings leading from the constant level chamber, one leading to the well and the other to the common chamber, a channel having a control opening leading from the well to the common chamber, and means for adjusting the size of the air opening into the well; substantially as described.

13. In a carbureter, an air passage, a constant level fuel chamber, an atmospheric well open to the air, a fuel supply to said well, an outlet from the lower part of the well, an L-shaped fuel supply passage communicating at one end with said outlet and terminating at the other end in said air passage, and an additional fuel supply leading from the constant level chamber and discharging into said L-shaped passage below the normal level of the fuel, substantially as described.

14. In a carbureter, an air passage, a con-

stant level fuel chamber, an atmospheric well open to the air, a fuel supply to said well, a calibrated control outlet from the lower part of the well, an L-shaped fuel supply passage communicating at one end with said outlet and terminating at the other end in said air passage, and an additional fuel supply leading from the constant level fuel chamber and discharging into said L-

shaped passage below the normal level of 10 the fuel, substantially as described.

In testimony whereof, I have hereunto set my hand.

ENO GAT C. PRADIER.
